NONLEAKING LUBRICANT

John C. Zimmer, Elizabeth, and Ejnar W. Carlson,
Roselle Park, N. J., assignors to Standard Oil
Development Company, a corporation of Delaware

Application March 29, 1935, Serial No. 13,616

8 Claims.

(Cl. 87—9)

The present invention relates to a method for improving lubricating oils for industrial uses, and more specifically for use in small machinery, textile mills and the like. The invention will be understood from the following description.

In the drawing, Figure 1 shows a graphical representation of the relation between oil consumption and power consumption in a journal bearing when used in connection with normal hydrocarbon lubricating oils and ordinary blended oils; and Figure 2 shows a similar representation of the comparison of oil consumption and power consumption of the oils now in use and of the present improved lubricants.

The type and quality of the base oils may be varied to suit the particular mill requirements and is, of course, a mineral lubricating oil which may be derived from any particular source; for example, from paraffine or naphthene crudes. The viscosity may vary throughout the range of the ordinary lubricating oils, say from about 75 seconds to approximately 2,000 seconds Saybolt at 100° F., depending on the load requirements for the particular bearings and other factors.

To the base oil is added a very small quantity, say less than .5% of a linear hydrocarbon polymer of isobutylene which is soluble in the oil and which is characterized by a molecular weight in excess of 30,000, this weight being determined by the Staudinger method, Die Hochmolekularen Organischen Verbindungen, H. Staudinger, 1932, Berlin. The actual amount of the polymer used in any particular depends to some extent on the particular circumstances, but quantities as low as .001% may be satisfactory, especially where the molecular weight of the polymer is very high, say above 100,000 and it is rare that more than .5% is ever used. For ordinary uses .1% is satisfactory.

The preferred polymer is produced from isobutylene which has been carefully purified and polymerized at a temperature below —50° C. and preferably at temperatures from —80 to —110° C. in the presence of active metal halide catalyst such as boron fluoride, although other catalysts may be employed. The low temperatures may be readily attained by carrying out the reaction in the presence of liquefied ethylene and allowing the same to evaporate at atmospheric pressure for example. It should be understood that there is an entire series of linear isobutylene polymers ranging in molecular weight from below 1,000 and up through the range indicated above, but there is a critical molecular weight which marks off the polymer satisfactory for the present purposes. Polymers having molecular weights below about 30,000 when added to the oil merely increase viscosity and the blends show an oil leakage-power consumption relation comparable to that displayed by a normal unblended hydrocarbon oil of the same viscosity range. However, when polymers above 30,000 are used, a totally different effect is noted and the oil consumption—power consumption relation is vastly different from that shown by normal oils of the

same viscosity. The polymers which are used, as stated before, have molecular weights above 30,000 and they may be as high as 100,000, 200,000 or even more.

5 A second ingredient of the oil is a soap. For this purpose the soda soaps are preferable, not only because of their cheapness but also because of their superior effects in the oil. Sodium oleate may be used or similar salts of other fat acids 10 such as stearic or palmitic, or mixtures of the same. Similarly, the alkali metal salts of synthetic acids may be used, particularly those prepared by the low temperature oxidation of oils and waxes. The amount of the soap is quite 15 small and is ordinarily less than 1% or 2%. As little as .1% shows a substantial effect, but .5% is usually employed.

While the soap is not an absolutely essential 20 ingredient of the present compounds, the latter are greatly improved by their addition. For example, in many cases the addition of the polymer to the oil will bring about a substantial decrease in oil consumption, but in many cases it brings about also a slight increase in power consumption. 25 However, on the addition of the soap, it is usually found that both the oil and the power consumption are considerably reduced. These effects, while noticeable in oils of all the viscosity ranges, are most noticeable in the range from 30 say 200 to 900 seconds Saybolt. Blends of oil and soap, which do not contain the polymer do not show the reduction of leakage.

The above substances are the principal ingredients of the present compounds although it 35 will be understood that other agents may be added, for example, higher alcohols, glycerine or glycol, fatty acids or esters, or other polar compounds which have the property of reducing frictional losses. Resins may also be added for 40 certain purposes, as well as aluminum soaps such as naphthenate, oleate or stearate or dyes, oxidation or pour point inhibitors none of which appear to interfere with the effect of the primary ingredients.

45 To illustrate the operation of the improved oils and the advantages of these compositions, the following examples may be considered.

Example 1

50 A large number of tests on straight minerals and mineral oils blended with soaps, fatty substances and the like were run on a bearing which consisted of a one-inch diameter steel shaft in a bronze sleeve of four-inch length. The oil 55 was fed at the center of the sleeve and then allowed to leak at the ends. This oil that leaked out was collected and leakage thus determined in cubic centimeters per minute. The runs were conducted at a speed of 1,200 R. P. M. obtained by means of a D. C. motor, and power consumption was measured by the difference in wattage consumed by the motor and the bearing, and by the motor alone.

60 It was found in general that power consumption increased with viscosity and oil consumption decreased therewith. The entire effect appears to be a viscosity phenomenon. The power consumption when plotted against leakage made 65 a fairly smooth curve which is represented in Figure 1 of the drawing. Since there was no attempt to control all of the variables, such as 70 temperature and the like, the curve is shown as a relatively narrow band rather than a line, 75 but the deviation from the mean was not great

and was undoubtedly within the experimental error at all times. Care was taken to insure that the bearing and motor were in substantially the same condition during all of these comparable tests.

5 In the above tests, the oil and oil blends represented on the curve varied in viscosity from 100 to 1,200 seconds Saybolt at 100° F. and samples included straight mineral oils of that viscosity range, mineral oils, oils containing lard oil, sodium 10 and potassium oleates or other soaps, aluminum stearate, sodium or calcium sulfonates, rosin and the like. It will be seen that the particular composition of the oil did not have any substantial effect on the relation between oil consumption 15 and power consumption.

Example 2

The figures given in this second series of tests 20 are not comparable with those included in the previous example although they were made on the same bearing. These tests were made at a later time when the normal oil consumption of the bearing had greatly increased by wear and the 25 motor had become less efficient. However, these tests are all comparable with each other.

The oils used herein were straight mineral oils 30 having viscosities of about 200, 500, and 900 seconds Saybolt at 100° F. respectively, and similar oils containing .1% of an isobutylene polymer, having a molecular weight of 60,000 to 100,000 together with .2% of sodium oleate.

The oil leakage and power consumption tests 35 were carried out according to the same procedure used in Example 1 and the data are plotted in Figure 2 of the drawing, curve A representing the straight mineral oils, while curve B represents the oils containing polymer and soap. The wide difference between the leakage and power consumption in the present compositions and the 40 straight mineral oils can be readily seen from the drawing.

Example 3

45 Data, some of it included in Example 2, on oils, unblended oil and oil blended with the soap alone or with the polymer alone and with the combinations of soap and polymer are shown in the table below.

Sample	Saybolt vis. at 100° F.	Oil consumption cc./min.	Power watts	50
Straight mineral oil	204	1.45	98	51
Same + .1% sod. oleate		.34	98	
+ .1% polymer	810	1.13	109	
Straight mineral oil		1.13	108	
Same + .1% sod. oleate				
Same + .1% sod. oleate + .1% polymer		.52	104	
+ .1% polymer	900	.72	118	
Straight mineral oil		.76	118	61
Same + .1% sod. oleate		.22	120	
+ .1% polymer				
Same + .1% sod. oleate + .1% polymer		.32	114	

6 The present compositions do not show any undesirable effects which would in any way hinder their employment for the most exacting uses. For example, it is found that the present oils can be scoured from clothes which they have stained without the slightest difficulty. In practical tests it is found that over 99% could be removed without difficulty and that they are equal to ordinary mineral oils in this respect. The oils have excellent lubricating properties sufficient to carry such loads as will be normally applied to them

in textile mills. They are also quite stable toward heat and the effects of air.

These oils may also be used in conjunction with emulsifiers, colloidal materials such as graphite, clay, zinc oxide, etc., sludge dispersers, low molecular weight oil thickeners, volatilized oils, waxes, extreme pressure agents, organo-metallic compounds, and the like.

10 The oils prepared according to this invention may in many cases be employed in soluble oil compositions for oiling textile fibers, cordage, leather and similar materials.

15 The present invention is not to be limited by any theories of the advantages of the present oils nor to any specific composition, molecular weight of polymer, or specific soap or combination of ingredients, but only to the following claims in which it is desired to claim all novelty 20 inherent in the invention.

We claim:

1. A lubricating oil adapted for low power consumption and leakage, comprising a mineral oil lubricating oil and a small quantity, less than 25 .5%, of an oil soluble linear polymer of isobutylene having a molecular weight in excess of 30,000.

2. A lubricating oil adapted for low power consumption and leakage comprising a mineral lubricating oil having a viscosity in the range of 30 about 75 to 2,000 seconds Saybolt at 100° F., and less than .5% of an oil soluble linear polymer of

isobutylene having a molecular weight in excess of 30,000.

3. A lubricating oil according to claim 2 in which the polymer has a molecular weight within the range from 30,000 to 300,000 and is present 5 in proportion within the limits of .001 to .5%.

4. A lubricating oil according to claim 2 in which the polymer has a molecular weight within the range from 30,000 to 300,000 and is present 10 in an amount from .001 to .1%.

5. An improved lubricating oil of low power consumption and leakage comprising a mineral lubricating oil having a viscosity in the range of 75 to 2,000 seconds Saybolt at 100° F., a small quantity, less than .5% of an oil soluble linear 15 polymer of isobutylene having a molecular weight in excess of 30,000 and a small quantity of an alkali metal soap.

6. A composition according to claim 5 in which 20 a sodium soap is used.

7. A lubricating oil for low power consumption and leakage comprising a mineral oil having a viscosity from about 200 to 900 seconds Saybolt at 100° F., less than .5% of a polymer of isobutylene having a molecular weight in excess of 30,- 25 000 and less than .1% of a sodium soap.

8. A composition according to claim 7 in which the amount of polymer is between .001 and .1% and the amount of soap is between .1 and 1%.
